APPARATUS FOR HEAT TREATING LATEX
ARTICLESValerio Ciampolini, Milan, Italy, assignor to Pirelli Sapsa
Societa per Azioni, Milan, Italy

Application December 1, 1953, Serial No. 395,546

Claims priority, application Italy December 2, 1952

14 Claims. (Cl. 18—6)

This invention relates to a method and apparatus for heat treating articles of latex, that is, of latex (or latex-foam) of natural rubber, synthetic rubber, or plastic materials, to solidify and/or vulcanize the same. More specifically, the invention relates to a method and apparatus for carrying out such heat treatment by means of fluent steam applied directly to the article in a sealed heat-treating zone under very low pressure e. g., a few thousandths of an atmosphere, with the steam being admitted to the heat treating zone cyclically in response to condensation of steam therein.

The principal advantages obtained from my improved method and apparatus are a remarkable saving in steam and a reduction in the time required to heat-treat the articles to be solidified and/or vulcanized, owing in part to precluding the mixture of air with the steam during the heat treating process. Other advantages of my invention appear from the description of the preferred form of apparatus for performing my improved process, as set forth hereinbelow.

Broadly comprehended, this apparatus consists of three principal parts, viz:

(1) A platform supporting the articles to be heat-treated, and having inclined planes to facilitate the discharge of the steam air condensate into a gutter trough, attached to the periphery of said platform;

(2) A light metal hood, fitting over said platform, and pivotally mounted, so that it can be raised by rotating it about said pivots, to allow charging and discharging of the material being treated. When in lowered position, the lower edge of the hood dips into the water contained in the aforesaid trough, and thereby forms a water-seal, which prevents entrance of air into said hood, but permits escape of air and steam therefrom as desired. A counter-weight for said hood is provided, in order to facilitate the raising of the hood from its horizontal (closed) position.

(3) Self-regulated means for automatically introducing steam into said hood, under a very low rate and accurately controlled pressure; said means comprising a manually operated by-pass valve for the starting operation, and a main valve, operated automatically by the raising and lowering of the hood, in accordance with the steam pressure therein.

The steam is fed into the closed hood through a specially arranged manifold located near the top of the hood and parallel to its longer side, at a very slow rate, so as to gradually displace the air in said hood, without forming a mixture therewith. The air thus displaced bubbles out through the water in the aforesaid trough, and when said air bubbles no longer appear (as indicated by steam bubbles), heat treatment can be started by closing the by-pass valve, whereupon the steam in the hood condenses, causing the hood to descend to its closed position, with its lower edge forming a water-seal with the water in said trough. As the hood approaches its lowermost position, it automatically contacts a push button on the aforesaid main valve, which thereupon opens and allows steam to enter the hood and act thereon in an opening direction. The balancing of forces acting on the hood brings it to a stable position which maintains a constant temperature therein, until the heat treatment is over; whereupon the by-pass valve is opened for a few seconds,

2

permitting the entrance of steam into the hood which raises it from engagement with the aforesaid water trough, after which the hood is further raised to full open position by hand.

With the foregoing and other objects in view which may be incident to my improvements, my invention consists of the combination and arrangements of steps and elements hereinafter described and illustrated in the accompanying drawings, in which the same reference characters denote the same parts in the several figures, and in which:

Fig. 1 is a side elevation of the apparatus, with the hood in closed position;

Fig. 2 is a front elevation of the apparatus, with the hood in closed position;

Fig. 3 is the same as Fig. 2, but with the hood in open position;

Fig. 4 is a plan view of the same apparatus shown in Figs. 1, 2 and 3;

Fig. 5-A is a central, longitudinal section, on an enlarged scale, of the steam-distributing manifold, and Fig. 5-B is a cross-section of the same, on a still further enlarged scale;

Fig. 6 is a side elevation (partly in section), on an enlarged scale, of the main steam regulating valve;

Fig. 7 is a section (on an enlarged scale) along the line 7—7 of Fig. 4;

Fig. 8 is a schematic view of the installation for automatic operation of the apparatus shown in Figs. 1-7;

Fig. 9 is a small scale schematic view of the automatic regulating portion of the installation shown in Fig. 8, during the starting phase of its operation;

Fig. 10 is the same as Fig. 9, during the working phase of operation; and

Fig. 11 is the same as Fig. 9, during the sprinkling phase at the end of the heat treatment operation.

Referring first to Figs. 1-4, the reference numeral 1 denotes a sheet metal platform for holding the articles or material to be heat-treated, supported by a base 2, comprising iron columns 3, connected by channel bars 4, electrically welded together to form a unitary structure. Platform 1 is formed with inclined planes 5, sloping from its center to its periphery (see Figs. 3 and 8), to which is attached a U-shaped metal gutter trough 6 (see Figs. 3 and 7). The slopes 5 of platform 1 facilitate the discharge of steam/water condensate falling thereon, into the adjoining trough 6. A pipe 7 conducts steam, under a very low pressure (e. g. a few thousandths of an atmosphere), from a source (not shown) to a main flow regulating valve 8, which is connected by a pipe 9 to a steam distributing manifold 10, as further described hereinbelow. Pipes 7 and 9 are also connected by a pipe 11 which bypasses valve 8, and through which the flow of steam into manifold 10 is controlled by a manually operated by-pass valve 12.

Fitting over platform 1 is a movable hood 13 of light, corrugated, sheet metal (preferably aluminum), having integral top and side walls, shaped as shown in Figs. 1, 2 and 4, and provided with reinforcing ribs 13a, as shown in Fig. 1. Hood 13 is made as light in weight as practicable, in order to reduce the mass of metal to be heated during each cycle of operation, and also to avoid the use of superfluous metal, taking into account the very low working pressure (e. g. $\frac{2}{3}$ grams per square centimeter) of the steam inside said hood. Attached to the four side-walls of hood 13 is a tubular metal frame 14, which extends to the rear of said hood and carries a counter-weight 15, as shown in Figs. 1-4. Attached to the extensions of frame 14 are a pair of trunnions 16, which are rotatably mounted in a bracket support 17, that in turn is carried by a beam 18, fixed to base 2, as shown in Figs. 1, 3 and 4. By means of this pivotal mounting, hood 13

may be raised from its horizontal (closed) position (Figs. 1 and 2, where the lower edges of its sidewalls dip into trough 6 (as shown in Fig. 7), and form a water-seal with the steam/water condensate therein, to a vertical (full-open) position (as shown in Fig. 3). The counterweight 15 balances the weight of hood 13, so that a very slight force is required to raise said hood from closed to full open position. When the hood 13 is in its horizontal (closed) position it hermetically seals its inclosed space from the outside atmosphere; and when in vertical (open) position, said hood permits the charging and discharging of the articles or material to be heat-treated from platform 1.

As shown in Fig. 6, the main steam regulating valve 8 is of the poppet type, comprising a conical seat 19 (preferably of stainless steel) which is engaged by a conical valve head 20, biased toward closed position by a spring 21. A push button 22, slidably mounted in a bracket 23 on the top of valve 8, is adapted to engage the upper end of a stem 24 of valve 20, so as to open said valve when said button is pushed downwardly, as hereinafter further described. When valve 8 is closed, steam can be admitted through by-pass pipe 11 and pipe 9 to manifold 10, by manually opening by-pass valve 12.

As shown in Figs. 5-A and 5-B, steam distributing manifold 10 comprises a pair of horizontal, telescoped pipes 25 and 26, of which the smaller and inner pipe 25 has on its bottom a series of perforations 27, spaced at increasing distances from its entrance end (connected to pipe 9). Perforations 27 are so positioned in order to obtain an even discharge of the steam throughout the length of the pipe 25. Were the perforations equally spaced, the steam would be discharged in greater quantity adjacent the downstream end of the pipe. Pipe 25 is supported at its left end by connecting pipe 9 and at its right end by a tubular support 28 (see Fig. 3). Pipe 26 is clamped to pipe 25 by an adjustable clamp 29 which, with spacers 30, holds said pipes in desired spaced relation to each other, as shown in Figs. 5-A and 5-B. Along the whole top of pipe 26 is a narrow slot 31 through which steam, discharged into pipe 26 through holes 27, escapes into hood 13.

The function of manifold 10 is to admit steam into hood 13, at a very low rate (which is controlled by the size and spacing of holes 27), simultaneously throughout the length of said hood (by means of slot 31); and since manifold 10 is located near the top of said hood (Fig. 1), the discharged steam first accumulates in the top of the hood, displacing the air therein. As the discharge of steam from manifold 10 continues, a greater volume of air is displaced by steam, progressing in a downward direction, until all the air is thus expelled from hood 13, through the water in trough 6, from which it escapes as bubbles. Manifold 10 is slightly inclined toward its entrance end (junction with pipe 9), in order to facilitate the draining of condensate in pipe 26, through the space between pipes 25 and 26 at their lower ends, onto platform 1, from which it drains into trough 6.

Manual operation

Before operation of the above described apparatus commences, trough 6 is filled with water, the level of which is thereafter automatically maintained by steam/water condensate draining from platform 1. After the articles or materials to be heat-treated are placed in position on platform 1, hood 13 is lowered to its horizontal (closed) position, and steam is admitted thereto through manifold 10, by manually opening by-pass valve 12. The steam issuing at a low speed through slot 31 in manifold 10 gradually fills hood 13 and displaces the air therein progressively from the top to the bottom of said hood. The expelled air escapes in the form of bubbles from the water in trough 6, and as soon as these air bubbles are followed by steam bubbles, said steam indicates to the operator that the working phase of the apparatus may begin.

The starting (warming up) phase may last from 30-40 seconds to from 4-5 minutes, depending upon the amount of material to be heated (i. e. greater weights of material require longer times). At the end of the starting phase, by-pass valve 12 is closed, whereupon the steam in hood 13 condenses to water, and since no outside air can enter hood 13, because of the water seal between the lower edge of said hood and trough 6, a slight vacuum is produced inside the hood. This vacuum causes hood 13 to descend slightly, which movement brings a rod 32, attached to frame 14, in contact with push bottom 22 (as shown in Figs. 1 and 2), and slightly opens valve 8, whereupon the resulting new influx of steam into hood 13 raises said hood and closes valve 8. These small up and down movements of hood 13 may take place without becoming apparent, and the hood rapidly assumes a balanced position, corresponding to an equilibrium between the rate at which the steam in hood 13 condenses (in consequence of thermal losses), and the rate of admission of steam through valve 8.

The heat treatment proceeds for a sufficient length of time to achieve its object (e. g. solidify liquid latex to desired consistency, or to vulcanize raw rubber to desired degree); whereupon the process is stopped, by manually opening by-pass 12 which admits sufficient steam to lift hood 13 so as to break its water seal in trough 6, and then lifting said hood to its vertical position by hand.

After the disengagement of hood 13 to its vertical position, the residual steam in the hood is dispersed and condensed by spraying it with finely atomized water, which is introduced into hood 13 by a plurality of spray nozzles 33, supplied with water by a pipe 34 from a source (not shown), (see Fig. 3). This spraying operation may require from 1 to 4 minutes (according to the load of material on platform 1), when using a flow of atomized water of 15-20 liters per minute, for the nearly total elimination of the residual steam.

Automatic Operation

The operation of the above described apparatus may be made automatic by employing a cycle-regulating device, having a plurality of pneumatically operated control valves, 35 and 36 (Fig. 8) for the remote control of the admission of steam into hood 13 during the first (starting) phase, the flow of atomized water during the third (spraying) phase, and the positioning of hood 13 during said spraying phase.

Valves 35 and 36 are supplied with compressed air by a pipe 37, having a pressure control valve 38 and connected to a source of compressed air (not shown). Valve 35 is connected by a pipe 39 to a diaphragm 40 of a valve actuator 41, having a stem 42 attached to diaphragm 40, and a spring 43 which opposes the upward movement of said diaphragm. Stem 42 is adapted to contact the left end 44 of a walking beam 45, pivoted at 46, and having its right end 47 adapted to contact push button 22 attached to main regulating valve 8, as shown in Figs. 8-11. When air is admitted by valve 35 to diaphragm 40, the latter raises stem 42 which then engages the left end 46 of beam 45, causing its right end 47 to depress button 22 and open valve 8, whereupon steam is admitted to hood 13, slightly raising said hood, so that rod 32 on frame 14 is disengaged from end 47 of beam 45, as shown in Fig. 9. Steam continues to enter hood 13, so long as diaphragm 40 holds valve 8 open, as just described.

The duration of this steam admission is predetermined and corresponds to the starting phase which is initiated by the opening of by-pass valve 12, as described above, under "Manual operation." When pneumatic valve 35 closes and interrupts the flow of air to diaphragm 40, the direct admission of steam into hood 13 ceases, whereupon the condensation of steam in hood 13 lowers said hood to its horizontal (water-sealed) position, as shown in Fig. 10. The lowering of hood 13 brings rod 32 into

contact with end 47 of beam 45 and push button 22, thus subjecting the operation of valve 8 to the oscillating movement of hood 13 (Fig. 10), thus beginning the phase of self-regulated heat treatment, as described hereinabove, under "Manual operation."

The duration of the period of heat treatment is predetermined by the object of said treatment, and upon its termination, pneumatic valve 35 opens, causing an instantaneous opening of valve 8, which disengages the hood 13 from its water-seal in trough 6. Nearly at the same time, valve 36 is opened, admitting compressed air through pipes 48 and 49 to cylinder 50, where it depresses piston 51 which (through connecting rod 52) lowers the free end of frame 14, and raises hood 13 until it disengages with the water in trough 6. At the same time, the opening of valve 36 admits compressed air, through pipe 48, to a diaphragm 53, which (against opposing spring 54) raises a stem 55 attached to a valve 56, thereby opening said valve and admitting cooling water, from a source (not shown), through pipes 57 and 58 and spray nozzle 59 to hood 13. (See Fig. 11.)

Since the cooling water must enter hood 13 some seconds after piston 51 has lifted said hood from engagement with the water in trough 6, the necessary delay is obtained by providing a small drain hole 60, in the lowest part of pipe 58, whereby said pipe is automatically emptied of water whenever valve 56 closes, and the time required for water to fill pipe 58, after passing valve 60 and before reaching spray nozzle 59, supplies said delay. If the time required to fill pipe 59 after opening valve 56 does not provide sufficient delay for the water entering hood 13, said delay time can be readily increased by interposing in line 58 a small accumulator tank, whose volumetric capacity is such that the time required to fill said tank equals said increased delay time. The area of drain hole 60 is so small that the loss of water escaping therethrough, during the spray phase, is immaterial. Alternatively, the necessary time delay, between the disengagement of hood 13 with the water in trough 6 and the entrance of water into said hood, can be obtained by the use of a third pneumatic valve (not shown), arranged in parallel with valve 36, and through which compressed air may be admitted to operate valve 56, independent of the admission of air to cylinder 50 by valve 36, whereby the time interval between the operation of piston 51 and the opening of valve 56 may be adjusted as desired.

At the end of the spraying (cooling) phase, pneumatic valve 36 closes valve 56, whereupon hood 13 is raised manually to its vertical position.

The succession of operations described above is controlled automatically by pneumatic valves 35 and 36, which are electrically actuated upon the closing of a switch 61 (Fig. 8), after hood 13 is first lowered to its horizontal position, at the commencement of a cycle of operations.

It will be understood that some adjustments in the operation of the above-described apparatus will be required depending chiefly upon the object of the heat treatment in each case. Thus, the timing of the various phases of the process will be different when the apparatus is used to solidify liquid latex of plastic materials, than when said apparatus is used for vulcanizing articles obtained from latex or latex-foam of natural or synthetic rubber. It will be further understood that the above described apparatus can also be used, in some cases, to vulcanize articles of natural or synthetic rubber obtained from compounds which vulcanize at a temperature of about 100° C. (i. e. the temperature of steam at substantially atmospheric pressure).

While I have shown and described the preferred embodiments of my invention, I desire it to be understood that I do not limit myself to the precise details of the process and apparatus disclosed by way of illustration,

as these can be changed and modified by those skilled in the art without departing from the spirit of my invention nor exceeding the scope of the appended claims.

I claim:

5. 1. In an apparatus for heat treating latex with fluent steam substantially at atmospheric pressure, the combination of an hermetically sealed heat treating chamber of definite initial volume, said chamber comprising a platform for supporting the material to be heat treated, and a movable hood disposed above said platform and material and hermetically sealed to said platform by an hydraulic seal; supply means for supplying steam to said chamber; and means operatively associated with said supply means and responsive to the movement of said hood for automatically regulating the supply of steam to said chamber in accordance with the condensation of steam in said chamber, whereby a thermal equilibrium and a predetermined constant temperature are maintained in said chamber during the period of heat treatment.

2. In an apparatus of the type described, the combination of a platform sloping outwardly and downwardly towards its peripheral edge, said edge being provided with a trough extending continuously therealong and adapted 25 to receive steam/water condensate draining from said platform, a movable hood disposed above said platform and including dependent sidewall means engageable in said trough as said hood is downwardly moved, said platform and hood comprising an hermetically sealed chamber when said sidewall means is engaged in liquid condensate in said trough, means for supplying steam to such hermetically sealed chamber, and means responsive to movement of said hood relative to said platform for regulating such supply of steam.

3. Apparatus according to claim 2, wherein said hood is pivotally mounted above said platform so that, by pivotal motion on its mounting, said hood may be raised from a horizontal position, wherein it forms a hydraulic seal with the liquid in said trough, to a vertical position, 40 wherein it completely uncovers said platform.

4. Apparatus according to claim 3, having means for discharging the steam admitted to said chamber near the top of said chamber so that said steam displaces the air in said chamber progressively downward from said top, 45 and said air escapes from chamber through the liquid in said trough, whereby the mixing of said steam and air is avoided.

5. Apparatus according to claim 4, wherein said steam discharging means comprises a distributing manifold consisting of a pair of spaced concentrically disposed tubes, the innermost one of said tubes being provided with a series of holes along its lower part spaced at increasing distances from the entrance of said manifold, and the outermost one of said tubes being provided with a narrow longitudinal slit, extending throughout substantially its entire length, through which steam is discharged into said chamber.

6. Apparatus according to claim 5 wherein said manifold is slightly inclined toward its steam entrance end, 60 so as to facilitate the discharge of liquid condensate in said outer tube, through the space between said inner and outer tubes, to said platform below said manifold.

7. Apparatus according to claim 3, having remote-controlled means for automatically starting and stopping the 65 admission of steam to said chamber, for starting and stopping the admission of cooling water to said chamber, and for raising and lowering said hood with reference to said platform.

8. In a heat treating apparatus of the type described, 70 the combination of a platform provided with a peripherally arranged trough adapted to receive liquid from the platform, a movable hood disposed above said platform, the dependent sidewalls of said hood being disposed for engagement with liquid in said trough to form a seal between said trough and platform, a steam dis-

charge manifold disposed within said hood, a steam line connected to said manifold, a flow control valve disposed in said steam line and provided with means biasing said valve to one position, and means associated with said hood and operatively associated with said valve for imparting actuating movement to said valve in response to movement of said hood relative to said platform, whereby admission of steam to said hood is regulated in accordance with condensation of steam within said hood.

9. In a heat treating apparatus of the type described, the combination of a platform provided with a peripheral trough disposed to receive liquid from said platform; a hood; means mounting said hood above said platform for movement toward and away from said platform, said hood being biased towards said platform with its depending sidewalls disposed for engagement with liquid in said trough, said hood and platform constituting a sealed chamber when said sidewalls are so engaged; supply means for admitting steam to said hood; flow control means operatively associated with said supply means; automatic means interconnecting said hood and said flow control means for actuating the latter solely in accordance with movements of said hood relative to said platform, and means operatively connected with said flow control means for actuating the same independently of said automatic actuating means for supply of steam to said hood regardless of the relative positions of said hood and platform.

10. In a heat treating apparatus of the type described, the combination of a platform provided with a peripheral trough disposed to receive liquid from said platform; a hood; means mounting said hood above said platform for movement toward and away from said platform, said hood being biased towards said platform with its depending sidewalls disposed for engagement with liquid in said trough, said hood and platform constituting a sealed chamber when said sidewalls are so engaged; supply means for admitting steam to said hood; flow control means operatively associated with said supply means; automatic means interconnecting said hood and said flow control means for actuating the latter solely in accordance with movements of said hood relative to said platform; spray means for applying cooling liquid to said hood to dissipate the steam therein; power means operatively connected with said hood and constructed to raise the same out of its operative position; means for actuating said power to raise said hood, and means actuated upon occurrence of such operation of said power means for supplying cooling liquid to said spray means.

11. In an apparatus for heat treating latex articles with fluent steam, the combination of upper and lower members cooperating to define a heat treating chamber, means mounting one of said members for movement toward and away from the other of said members between an operative position in which said members are adjacent to each other and a second operative position in which said members are spaced apart, seal means cooperating with both of said members to form a fluid seal therebetween, said seal means operatively engaging both of said members in sealing relationship throughout movement of said one member between said operative positions, whereby said chamber is maintained hermetically sealed during such movement, said one member being biased toward said other member, supply means for supplying steam to said chamber, and means operatively associated with said supply means and responsive to the movement of said one member between said operative positions for automatically regulating the supply of steam to said chamber in accordance with the condensation of steam in said chamber, whereby a thermal equilibrium and a predetermined constant temperature are maintained in said chamber during the period of heat treatment.

12. In an apparatus for heat treating latex articles for a predetermined period by contact with steam at a substantially constant temperature and pressure, the combi-

10 nation of a base, a hood disposed above said base and cooperating therewith to generally define an enclosed heat treating space, means mounting said hood for movement toward and away from said base between a first operative position in which said hood is disposed immediately adjacent said base and a second operative position in which said hood is spaced from said base, seal means cooperating with said base and hood to form a fluid seal therebetween, said seal means operatively engaging both said base and said hood in sealing relation throughout movement of said hood between said operative positions, whereby said enclosed space is maintained hermetically sealed as the volume thereof is varied by movement of said hood, said hood being biased toward said base, supply means arranged to admit steam to said enclosed space, control means for regulating the admission of steam by said supply means, and means operatively associated with said control means and responsive to a predetermined movement of said hood and thus to occurrence of a predetermined change in volume of said enclosed space, for actuating said control means to regulate the admission of steam to said enclosed space by said supply means.

15 13. An apparatus constructed in accordance with claim 12 and in which the means mounting said hood for movement relative to said base includes a counter-balance so constructed and arranged that increasing steam pressure within said chamber is effective to cause movement of the hood away from the base and decreasing steam pressure within said space is effective to allow movement of the hood toward said base under the biasing action of gravity.

20 14. In an apparatus for heat treating latex articles for a predetermined period by contact with steam at a substantially constant temperature and pressure, the combination of a heat treating chamber comprising two members cooperating to define an enclosed space and seal means cooperating with both of said members to maintain said space hermetically sealed, mounting means supporting one of said members for movement between an inactive position removed from the other of said members, such that articles to be treated may be inserted in said chamber, and a position adjacent said other member, said mounting means allowing relatively free movement of said one member toward and away from said other member throughout a range of operative positions adjacent said other member, said seal means operatively engaging both of said members in sealing relation throughout said range of operative positions, whereby said space is maintained hermetically sealed as the volume thereof is varied by movement of said one member, said one member being biased toward said other member when occupying said operative positions, supply means arranged to admit steam to said enclosed space, control means for regulating the admission of steam by said supply means, and means operatively associated with said control means and responsive to a predetermined movement of said one member in said range of operative positions, and thus to occurrence of a predetermined change in volume of said enclosed space, for actuating said control means to regulate the admission of steam to said enclosed space by said supply means.
